UNITED STATES PATENT OFFICE.

GUSTAV MEYERSBERG, OF BERLIN, GERMANY, ASSIGNOR TO GENERAL ELECTRIC COMPANY, A CORPORATION OF NEW YORK.

MULTISTAGE TURBINE.

No. 889,171.

Specification of Letters Patent.

Patented Dec. 25, 1906.

Application filed May 18, 1905. Serial No. 261,081.

To all whom it may concern:

Be it known that I, GUSTAV MEYERSBERG, a subject of the Emperor of Austria-Hungary, residing at Berlin, Germany, have invented certain new and useful Improvements in Multistage Turbines, of which the following is a specification.

In the design and construction of elastic-fluid turbines for marine purposes there are two principal conditions to be considered—*i. e.*, a favorable steam consumption on one hand and the smallest possible weight and space on the other. The first condition depends, presupposing a good detail construction, on the kind of stage division. Stages in which the *vis viva* of the steam flowing from the nozzles is abstracted by a single row of wheel-buckets in one operation are more effective than those having two or more rows of wheel-buckets arranged to abstract the *vis viva* in two or more operations. The greater the number of operations required to abstract the velocity of the steam in each stage the lower will be the degree of effectiveness of each stage. The magnitude of the drop in pressure in the stage also has to be considered in this connection. A small drop in pressure per stage means a more effective utilization of the steam than a large drop. On the other hand, if the velocity of the steam is abstracted by a number of successive operations, as by the use of a number of rows of wheel-buckets and the necessary intermediates, the said operation being accompanied by a large drop in pressure per stage, the total number of stages for a given machine can be reduced. For example, with a certain difference in terminal pressures three stages will be necessary to efficiently abstract the energy of the steam or other motive fluid where each stage has four rows of wheel-buckets, while with the same bucket velocity and three rows of wheel-buckets per stage five stages will be necessary. Assuming the same conditions with two rows of wheel-buckets per stage, eleven stages will be necessary, and with one row of wheel-buckets forty-five stages will be necessary.

The present invention has for its object to provide a turbine which is efficient in its utilization of the motive fluid without, however, being excessively heavy.

In the accompanying drawings, Figure 1 shows in longitudinal section a turbine rep-

resenting one embodiment of the invention, 55 and Fig. 2 is a sectional view of an expanding nozzle.

The casing 1 is divided into stages 2, each having a plurality of rows of buckets, and stages 3, each having a single row of wheel-buckets per stage. Those stages having several rows of buckets per stage are located at the high-pressure end of the turbine, while those having only a single row of buckets per stage are located on the low-pressure or 60 vacuum end of the turbine. This arrangement has the advantage that the pressure of the steam is quickly and materially reduced, thereby dispensing with strong-walled and heavy casings and reducing the losses due to 65 steam friction, which losses are less with low-pressure steam than with high.

Owing to the use of a single row of wheel-buckets per stage in the low-pressure stages, the utilization of the steam is carried to the 70 extreme. In the high-pressure stages, where the volume of motive fluid is small, only a part of the wheel is active—that is to say, the nozzles or devices 4, discharging fluid to the wheel, only cover a limited arc of the 75 bucket circumference. In this way wheels of large diameter may be employed. In the low-pressure stages, however, all of the buckets in each stage are utilized. To state the matter in a different way, the high-pressure 80 stages operate on the partial-flow-injection plan, while the low-pressure stages operate on the total-flow-injection plan. By using the entire bucket circumference of the 85 low-pressure stages all of the buckets may be 90 mounted on a single drum and arranged concentrically one row behind the other. Instead of a single drum, two or more may be used and placed one behind the other on the shaft to form, in effect, a single drum. 95 This arrangement dispenses with the dia-phragms or partitions 5, used between the high-pressure stages, and at the same time decreases the axial length of the machine. The nozzles or other devices 5, which discharge fluid against the buckets of the low-pressure wheels, are supported by the casing.

Under certain conditions it may be desirable to follow the total-injection plan into the high-pressure stages, as well as in the 100 low; but this results in increasing the length of the machines. On the other hand, it may be desirable to follow the partial-injection

plan as to some of the low-pressure stages; but this also will increase the length of the machine.

If a symmetrical arrangement is desired, it is possible to divide the low-pressure stages into two or more parts and to arrange them on opposite sides of the high-pressure stages and let the steam flow through them one after the other or in parallel. Moreover, the shafts for the high and low pressure stages may be mechanically separate and rotate at the same or different speed. It is thus possible to obtain a high and one or more low pressure turbines with the most favorable distribution possible between weight and length of structure, on the one hand, and degree of effectiveness on the other.

In the first stage the velocity of the fluid is abstracted by four operations. Hence four rows of wheel-buckets are provided, while in the second and third stages the energy is abstracted by three operations, and hence three rows of wheel-buckets are provided. From this construction it follows that the drop in pressure is greater in the first stage than in the subsequent stages and also that the velocity of the motive fluid is greater.

In Fig. 2 I have shown a part of a section-alized nozzle in cross-section, whose expansion ratio is such that it converts a greater amount of pressure into velocity than do the nozzles of the succeeding stages. No attempt has been here made to show the exact expansion ratio necessary on account of the extremely small scale of the drawing.

I have shown and described one means for obtaining a higher velocity in the first stage than in the subsequent stages; but it is to be understood that the invention in its broader aspects is not specifically limited thereto, since the desired relation of steam velocities in the different stages can be obtained by other means, as is well understood in the art to which this invention relates.

In accordance with the provisions of the patent statutes I have described the principle of operation of my invention, together with the apparatus which I now consider to represent the best embodiment thereof; but I desire to have it understood that the appa-

ratus shown is only illustrative and that the invention can be carried out by other means.

What I claim as new, and desire to secure by Letters Patent of the United States, is—

1. In a multistage turbine, the combination of high-pressure stages, having wheels which are partially supplied with motive fluid, the motive fluid in the first stage having a greater velocity than that in the subsequent stages, low-pressure stages having wheels which are fully supplied with motive fluid, and partitions which are located between the high-pressure stages only.

2. A turbine having high and low pressure stages, in combination with rows of wheel-buckets in each of the high-pressure stages for abstracting the energy of the motive fluid by successive fractions, a single row of wheel-buckets in each of the low-pressure stages for abstracting the energy of the fluid in each stage in a single operation, expanding nozzles for discharging fluid to the high-pressure stages, nozzles or devices for discharging fluid to the low-pressure stages, and partitions which are located between the high-pressure stages only.

3. A turbine having high and low pressure stages, in combination with rows of wheel-buckets in each of the high-pressure stages, for abstracting the energy of the motive fluid by successive fractions, nozzles or devices which extend over a limited arc and discharge motive fluid against a portion only of the buckets in each of the high-pressure stages for abstracting the energy of the fluid in each stage by successive operations, the nozzles of the first stage converting a greater percentage of the pressure into velocity than those of the subsequent stages, nozzles or devices for the low-pressure stages which surround the wheel-shaft and discharge fluid against all of the wheel-buckets, and partitions which are located between the high-pressure stages only and support the high-pressure nozzles or devices.

In witness whereof I have hereunto set my hand this 18th day of April, 1905.

GUSTAV MEYERSBERG.
